UNITED STATES PATENT OFFICE.

CHARLES GERHARDS, OF CHICAGO, ILLINOIS.

DESIGN FOR A WALL TABLE.

Application filed March 14, 1924. Serial No. 8,929. Term of patent 7 years.

To all whom it may concern:

Be it known that I, CHARLES GERHARDS, a citizen of Germany, residing at Chicago, in the county of Cook and State of Illinois, have invented a new, original, and ornamental Design for Wall Tables, of which the following is a specification, reference being had to the accompanying drawing, forming part thereof.

The figure is a view of a wall table, in perspective, showing my new design.

I claim:

The ornamental design for a wall table, as shown.

CHARLES GERHARDS.

Witnesses:

HARRY H. HITZEMAN,
ALBERT HOLBER.
